C. W. WYMAN

MINING MACHINE

Filed Sept. 1, 1922

UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

MINING MACHINE.

Application filed September 1, 1922. Serial No. 585,643.

My invention relates to mining machines. It has for its object to provide an improved safety device for a mining machine. A further object is to provide an improved cutter chain disconnecting means, and more especially an improved disconnecting means for a cutter chain on a coal mining machine of the self propelled flexibly fed type. A still further object is to provide an improved means for automatically disconnecting the cutter chain clutch while loading such a machine onto its self propelled truck. These and other objects and advantages of my invention will, however, hereinafter more fully appear.

In the accompanying drawings I have shown for purposes of illustration two embodiments which my invention may assume in practice.

20 In these drawings:—

Fig. 1 is a side elevation of a mining machine in process of loading on its self propelled truck and equipped with my improvement, the loaded position of the mining machine being indicated by dotted lines.

25 Fig. 2 is a partial vertical sectional view taken substantially on line 2—2 Fig. 1.

Fig. 3 is a partial horizontal sectional view taken substantially on line 3—3 Fig. 1.

30 Fig. 4 is a detail side elevation of a portion of my improved mechanism.

Fig. 5 is a detail view of a modified form of my invention.

In this illustrative construction, I have 35 shown a mining machine of the usual room and pillar type including a frame 1 slidable over the mine bottom and having a projecting cutter bar 2 carrying an endless bit carrying cutter chain 3, the cutter chain being driven in a well known manner from 40 a motor 4 on the frame through a suitable driving mechanism (not shown) connected to the cutter chain sprocket 5. Herein, as in a usual construction, flexible feeding means 45 in the form of a chain 6 is also adapted to use in feeding the mining machine relative to the face of the mine and to be driven from a suitable feed operating member 7, driven in a well known manner from the motor 4. The mining machine 1 is also shown to be adapted to be mounted on a wheel truck including a machine guiding frame 8 and driven from the mining machine motor in a well known manner, electric current be-

ing supplied to the motor through a cable 55 reel 9 on the truck.

Referring more particularly to the cutter chain drive it will be noted that between the sprocket 5 and the driving means therefor is interposed a clutch member comprising a usual stationary clutch member 10 rotatable with the cutter chain drive sprocket 5 and a cooperating clutch member 11 having fingers 12 adapted to cooperate with suitable notches 13 in the member 10. As 60 in a usual construction, it will also be observed that this member 11 is provided with controlling lever mechanism including a control lever 14 pivoted to the frame at 15 at its inner end and pivotally connected 65 through an adjustable link 16 with a cooperating lower fork link 17 pivotally connected to the member 16 at 18 and pivoted on the frame at 19 and having its inner ends operatively engaging lateral pins 20 on 70 standing extensions on the opposite sides of the member 11, the mechanism cooperating in such a manner as to raise or lower the member as the lever 14 is moved up or down about its pivot. As the specific construction of this clutch does not itself enter into 75 my invention and is of a well known type it is believed that a more detailed description is unnecessary. The control lever 14 is also provided with a reduced portion 21 on 80 its outer end which portion extends through, and is movable, herein vertically, in a plurality of apertures 22 and 23, herein substantially circular in form, in the side wall of the frame, and connected by a vertically 85 disposed slot 24 of uniform cross section. It will be observed that this reduced portion 21 carries slidably thereon an operating member 25, the outer end of which is suitably recessed at 26 and carries within said 90 recess a coiled spring 27. As shown, this member 25 also has a cylindrical extension 28 adapted to fit in the openings 22 and 23 in the frame 1, and the same is further provided with an enlarged grip or engaging 95 portion 29 adapted to be gripped manually by the operator. A retaining washer 30 is also provided on the reduced portion 21 to retain the spring 27 in place and to prevent dirt, or the like, from interfering with the 100 action of the spring.

In my improved construction it will be observed that a cam member 31 is carried on

a suitable upstanding support 32 located on the side of the frame 8 and adjacent the handle 25, said support being herein bowed laterally at 34 to permit passage of the feed chain over its idler 35. This member 31 is provided with a beveled edge 36 adapted to engage the operating member 25 on rearward movement of the machine 1 in its truck frame as for example during the machine loading operation. On said member 31 and extending rearwardly and outwardly from said beveled edge 36 is also an engaging surface 37 which against the action of spring 27, forces the cylindrical extension 28 from the aperture 22 in such manner as to release the control lever from the frame 1. Leading rearwardly and downwardly from the surface 37 is also a surface 38 which engages the member 25 and forces the same downwardly, the portion 21 passing freely through the slot 24 connecting the two apertures and registering with the lower aperture thereby releasing the clutch mechanism and stopping the cutter chain.

25 The operation of my improved device is as follows. The flexible feeding member 6 is attached to a suitable abutment at the rear end of the transport truck and the mining machine is drawn up onto the truck by means of the feed operating member 7 in a well known manner. If the cutting mechanism is running, the clutch operating member 25 is locked in its upper or on position. As the machine is loaded onto the truck the clutch operating member engages the bevel edge 36 of the cam member 31 and the clutch operating member is forced outwardly by the cam surface 37 drawing the cylindrical extension 28 on the member 25 against the action of the spring 27 from the aperture 22 on the machine frame 1. As the machine continues its backward movement the downwardly extended cam surface 38 forces the lever 14, with the operating member 25, downwardly through the vertically disposed slot 24 into registration with the aperture 23 thereby forcing the fingers 12 out of the notches 13 and stopping the cutter chain. The machine is then in position to be driven from the room. When the mining machine is to be unloaded the flexible feeding means 6 is attached to a suitable point in advance of the truck and the machine is drawn outwardly, releasing the operating member 25 from the cam 31, allowing the action of the spring 27 to force the cylindrical extension 28 into engagement with the lower aperture 23, and locking the lever 14 and the clutch in off position. To start the cutter chain, the operating member 25 must be manually pulled out from the aperture 23 and moved up through the slot 24 to its clutch connecting position.

65 In Fig. 5 it will be observed that I have shown a modified form of mechanism for

preventing the operator from leaving the main clutch thrown in. On the support 32 there is here mounted a switch, generally indicated by the numeral 39 and comprising an engaging portion 40, normally held in operative position by a spring 41, adapted to engage the operating member 25 when in operative position, this when the machine moves rearwardly on the truck. This member 25 forces the portion 40 rearwardly and as this said portion is pivotally connected, as at 42 to a crank 43 formed on a knife switch 44 controlling the machine motor circuit, this rearward movement of the member 40 throws out the knife switch stopping the motor and further movement of the mining machine until the member 28 is manually pulled outwardly and downwardly through the slot 24 and into the aperture 23, thereby throwing out the main clutch. In this position the motor may again be started and the machine fully loaded on the truck, the operating member 25 passing under the switch 39.

As a result of my improvement it will be observed that the cutter chain is automatically disconnected or rendered inoperative during the loading operation in such manner as to eliminate the injuries to operators and the damage to the machines which have heretofore been brought about, my invention making it impossible for a forgetful operator to leave the cutter chain clutch in after loading the machine on the truck, stop the motor until the jacks and slack chain have been piled on the cutter bar, and then start the motor to drive the truck out of the room with the cutter chain clutch still connected. It will also be observed that in the mechanical form of my invention, it is made impossible for the cutter chain to start prematurely while the machine is being unloaded, the clutch being maintained out until the machine moves forward on the truck and even then being automatically locked in out position so that the chance of prematurely rotating the cutter chain is minimized.

While I have in this application specifically described two embodiments which my invention may assume in practice it will be understood that these forms are shown for illustrative purposes only and that the invention may be modified and embodied in various forms without departing from the spirit or the scope of the appended claims.

What I claim as new and desire to secure by Letters Patent is:

1. In a mining apparatus, a mining machine adapted to slide on a mine bottom having cutting mechanism, a truck adapted to receive said machine, and means for automatically rendering said cutting mechanism inoperative as said machine is moved relative to said truck.

2. In a mining apparatus, a mining machine adapted to slide on a mine bottom having cutting mechanism, a truck adapted to receive said machine, and means for automatically rendering said cutting mechanism inoperative as said machine is loaded on said truck. 70
3. In a mining apparatus, a mining machine truck, a mining machine adapted to slide on a mine bottom having cutter chain driving means said machine being movable onto said truck, and automatic means to disconnect said driving means on movement of said machine relative to said truck. 75
- 10 4. In a mining apparatus, a mining machine adapted to slide on a mine bottom having a clutch, a truck adapted to receive said machine, and means for automatically disconnecting said clutch as said machine moves relative to said truck. 80
- 15 5. In a mining apparatus, a mining machine adapted to slide on a mine bottom having a cutter chain and a clutch therefor, a truck adapted to receive said machine, and means carried by said truck to throw out said clutch as said machine moves relative to said truck. 85
- 20 6. In a mining apparatus, a mining machine adapted to slide on a mine bottom having a cutter chain and a clutch therefor, a truck adapted to receive said mining machine, and automatic means to disconnect said clutch on movement of said machine on said truck. 90
- 25 7. In a mining apparatus, a mining machine having cutting mechanism, a clutch therefor, and locking means for said clutch, a mining machine carrying truck, and means carried by said truck to release said locking means. 95
- 30 8. In a mining apparatus, a mining machine having cutting mechanism, a clutch therefor, spring controlled locking means for said clutch, a mining machine carrying truck, and means carried by said truck to release said locking means. 100
- 35 9. In a mining apparatus, a mining machine having cutting mechanism, a clutch therefor, spring controlled locking means for said clutch including apertures in said machine, a mining machine carrying truck, and means carried by said truck to release said locking means. 105
- 40 10. In a mining apparatus, a mining machine having a continuous cutter chain, driving means therefor, and a clutch interposed between said cutter chain and said driving means, a mining machine receiving truck, and means carried by said truck to automatically disconnect said clutch to stop said cutter chain. 110
- 45 11. In a mining apparatus, a mining machine having a cutter chain, a cutter chain driving sprocket, a clutch therefor, operating means for said clutch, and locking means for said clutch and locking means for said operating means normally locked in an aperture in said machine, a mining machine receiving truck, and a cam carried by said truck to automatically re- 115
- 50 12. In a mining apparatus, a mining machine having a continuous cutter bit carrying chain and driving means for said chain, a mining machine truck, and means carried by said truck and operative on movement of said machine relative to said truck to render 75 said driving means inoperative. 120
- 55 13. In a mining apparatus, a mining machine having a continuous cutter chain, a cutter chain drive sprocket, driving means for said sprocket, a clutch interposed between said driving means and said sprocket, operating means for said clutch and locking means for said operating means, a machine carrying truck, and means carried by said truck to automatically release said locking 85 means and operate said operating means. 125
- 60 14. In a mining apparatus, a mining machine having a continuous cutter chain and a clutch therefor and flexible feeding means including a flexible feeding member, a truck adapted to receive said mining machine, and automatic means to release said clutch as the mining machine moves relative to said truck along said feeding means. 90
- 65 15. In a mining apparatus, a mining machine having a cutter chain and a clutch therefor, a truck adapted to receive said machine, and a cam carried by said truck and adapted to disconnect said clutch as said machine moves relative to said truck. 100
- 70 16. In a mining apparatus, a mining machine having a cutter chain and a clutch therefor, a truck adapted to receive said machine, and means including angularly disposed cam surfaces carried by said truck 105 and adapted to disconnect said clutch as said machine moves relative to said truck.
- 75 17. In a mining apparatus, a mining machine having cutting mechanism, a truck adapted to receive said machine, and a cam carried by said truck for automatically rendering said cutting mechanism inoperative as said machine is moved relative to said truck. 110
- 80 18. In a mining apparatus, a mining machine having a cutter chain, a clutch therefor, operating means for said clutch, and spring controlled locking means for said operating means, a mining machine truck, and cam means thereon to automatically overcome said spring controlled locking means and release said clutch on rearward movement of said machine on said truck. 115
- 85 19. In a mining apparatus, a mining machine having cutting mechanism and a clutch therefor, clutch operating means, and locking means for said operating means normally locked in an aperture in said machine, a mining machine receiving truck, and a cam carried by said truck to automatically re- 130

lease said locking means from said aperture on rearward movement of said machine on said truck.

20. In a mining apparatus, a mining machine having a clutch and locking means for said clutch, a mining machine receiving truck, and means engageable with an element of said locking means to release the same and automatically throw out said clutch on movement of the mining machine on said truck.

21. In a mining apparatus, a mining machine having a clutch and locking means for said clutch, a mining machine receiving truck, and a cam engageable with an element of said locking means to release the same and automatically throw out said clutch on movement of the mining machine on said truck.

22. In a mining apparatus, a mining machine having cutting mechanism, a truck adapted to receive said mining machine, and means for automatically rendering said cutting mechanism inoperative as the mining machine moves relative to said truck having provision for retaining the same inoperative while said machine is on said truck.

23. In a mining apparatus, a mining machine having cutting mechanism and a clutch therefor, and pivoted adjustable operating means for said clutch, a mining machine receiving truck, and a cam carried by said truck to automatically actuate said operating means to disconnect said clutch on movement of the mining machine on said truck.

24. In a mining apparatus, a mining machine having a cutting mechanism and a clutch therefor, operating means for said clutch, and locking means for said operating means including a member disposable in slot connected apertures in said mining machine, a mining machine receiving truck, and cam means operative on rearward movement of said machine on said truck and carried by said truck for automatically releasing said member from one of said apertures and force-

ing said operating means through said slot and said member into registration with the other aperture.

25. In a mining apparatus, a mining machine having a cutting mechanism and a clutch therefor, operating means for said clutch, and locking means for the latter including a spring controlled member on said operating means and slot connected apertures in said machine, a mining machine receiving truck, and a cam carried by said truck and operative to release said spring controlled member from one aperture and force said operating means downward through the slot into registering position with the other aperture on rearward movement of said machine on said truck and to release said spring controlled member on forward movement of said machine on said truck.

26. In a mining apparatus, a mining machine having cutting mechanism, a clutch therefor, locking means for said clutch, and manual and automatic means including a common element for rendering said clutch inoperative.

27. Mining apparatus comprising, in combination, a supporting truck, a mining machine comprising cutting mechanism and adapted in one position on said truck to drive the latter, and means for automatically preventing drive of said cutting mechanism when said machine is in said position.

28. Mining apparatus comprising, in combination, a motor, cutting mechanism driven thereby, a supporting truck on which said motor and said cutting mechanism are transported, said motor being operative to effect propulsion of said truck, and means for automatically preventing drive of said cutting mechanism by said motor when said cutting mechanism occupies a predetermined position on said truck.

In testimony whereof I affix my signature.

CHARLES W. WYMAN.
